UNITED STATES PATENT OFFICE.

GEORGE JACOB DEINES, OF RUSSELL, KANSAS.

MATCH-BOX.

1,257,817.

Specification of Letters Patent. Patented Feb. 26, 1918.

Application filed April 26, 1915, Serial No. 23,928. Renewed January 8, 1918. Serial No. 210,947.

To all whom it may concern:

Be it known that I, GEORGE J. DEINES, a citizen of the United States, residing at Russell, in the county of Russell and State 5 of Kansas, have invented new and useful Improvements in Match-Boxes, of which the following is a specification.

This invention relates to match boxes and more particularly to mono-delivery match 10 boxes, the principal object of the invention being to provide simple and efficient mechanism by which single matches may be projected from the safe or box into position to be removed.

Another object of the invention is to provide a match safe having a discharge opening removed from the hopper and with means for feeding single matches from the hopper into position to be projected through 20 the discharge opening for removal.

Still another object of the invention is to provide a safe of this character in which the matches are singly fed into position to be projected through a discharge opening and 25 in which the projecting mechanism is arranged to operate to project a single match through the opening upon each retrograde movement of the feeding mechanism.

Further objects of the invention will appear as the following description is read in connection with the accompanying drawing, which forms a part of this application, and in which:

Figure 1 is a front elevation.

Fig. 2 is a top plan view with the cover plate removed.

Fig. 3 is a rear elevation with the door and the upper portion of the rear plate removed and showing the feeding plates in 40 partially raised position.

Fig. 4 is a vertical sectional view on the line 4—4 of Fig. 3.

Fig. 5 is a horizontal section on the line 5—5 of Fig. 4.

Fig. 6 is a detail perspective view of the discharge arm and its associated actuating shaft.

Fig. 7 is a perspective view of the top plate looking from the underneath side.

Referring more particularly to the drawing, 1 represents a case consisting of a front plate 2, side plates 3, bottom plate 4, top 5 and rear plate or back 6 which latter part is provided with a door 7 which may 55 be opened to fill the hopper with matches,

as will be readily understood. Secured between the sides 3 and extending vertically in echelon and in parallelism to the front 2 are partition members 8 and 9 whose upper edges are inclined rearwardly as indicated 60 at 10. Between the partition member 9 and the front plate there is slidably mounted a feeding plate 11 whose upper edge is also inclined, as shown at 12, the highest portion thereof being flush with the lowest portion of the upper edge of the partition 9. Between the partition 9 and the partition 8 is a second feeding plate 13 having its upper edge arranged with relation to the partition 8 in a similar manner to the arrangement 70 previously spoken of with relation to the partition 9 and feeding plate 11. In the rear of the partition 8 and between the same and the hopper bottom 14 is a third feeding plate 15 whose upper edge is arranged on 75 an incline parallel with the inclination of the bottom 14 of the hopper and arranged to normally align therewith. When in depressed position all of the feeding plates rest upon a transverse shaft 16 which is 80 journaled in a bearing plate 18 secured across the sides 3 adjacent the bottom 4 and covered by the rear plate 6. This shaft 16 carries an actuating lever 19 slotted at 20 to free itself of the partition 9, the partition 85 8 being cut away as shown at 21 to permit the passage of said lever. This lever when the shaft is turned elevates all of the feeding plates simultaneously, as will be more clearly hereinafter understood. 90

Journaled in a groove 22 in the plate 2 is a vertical shaft 23 having a spiral groove 24 formed therein which is engaged by a pin 25 projecting horizontally from the front of the feeding plate 11. The upper end of 95 the shaft carries a laterally or horizontally projecting arm 26 which is grooved to receive a match and which normally lies at right angles to the front 2. When turned by the pin 25 operating within the groove 100 24 the arm is thrown to a position in a plane with the front 2 and over the top thereof, as is shown by the dotted lines in Fig. 2. In this position the arm is adapted to receive a match which will be discharged off of the 105 inclined upper edge of the feeding plate 11 and retain the same in such position until the shaft 23 is turned by a retrograde movement of the feeding plate 11. To properly hold the match and to prevent its accidental 110

falling off of the upper edge of the front upon which half of the match rests as will be readily understood the upper edge of the front has secured thereto a plate 27 which is 5 provided with a vertical retaining flange 28 arranged to engage that portion of the match not held within the grooved arm 26. Secured across the front of the case adjacent the top is a plate 29 having a transverse 10 opening 30 therein whose lower edge is flush with the upper edge of the plate 27, as shown.

In the operation of the device, the shaft 16 is rotated by means of a knob or operating handle 31 and thus through the lever raising all of the feeding plates 11, 13 and 15 when the plate 15 is elevated to its full height the match which rests upon its upper edge will be discharged upon the upper inclined edge of the partition 8 and will be retained in such position until the upper edge of the feeding plate 13 is brought into alignment with the upper edge of the partition 8 in the retrograde movement of the 20 feeding mechanism and the feeding plates are again elevated and the feeding plate 13 has its upper inclined edge aligned with the partition 9. The match then on the feeding plate 13 will drop onto the partition 9 and will subsequently be discharged onto the 25 feeding plate 11 when the parts next again assume their normal position. Upon the third raising of the feeding plates the match which has now been discharged upon the upper inclined edge of the feeding plate 11 will be discharged onto the plate 27 and arm 26 which has previously been turned to align with the front and into parallelism with the feeding plates. When the parts are again 30 returned to normal position by the gravity of the feeding plates the shaft 23 will be turned so that the arm 26 will be positioned at right angles to the front and the portion of the match which rested upon the plate 27 35 will be projected through the opening 30, thus placing the same in position for ready removal from the match case. It will be clearly understood that when the device is once started there will always be a match 40 resting upon the top of each feeding plate and as one match is discharged into the projecting arm the succeeding lower matches which have been previously supported upon the feeding plates will be discharged onto the 45 partitions when the feeding plates are in their highest position and subsequently 50 discharged onto the feeding plates when 55

they are again lowered to have their upper edges aline with the partitions.

In order to prevent movement of the match in the grooved arm 26 by reason of centrifugal force I preferably secure to the top 5 a guard plate 32 which covers the end of the grooved arm as will be readily seen from an inspection of Figs. 4 and 6. I also 65 preferably secure to the plate an inclined guide rod 33 and a retaining strip 34 all of which serve to prevent accidental discharge of the match from the arm 26, as will be readily understood.

70

What is claimed is:—

1. A mono delivery match safe comprising a casing having a discharge opening and a hopper, independent vertically movable feed plates for arranging the matches in 75 position to be projected singly through the opening, an operating lever arranged transversely below the feed plates for their simultaneous operation, and means operated by a movement of one of the feed plates for 80 projecting a match through the opening.

2. A mono delivery match safe comprising a casing having a discharge opening and a hopper, a plurality of match supporting members arranged in echelon, a plurality of sliding members arranged in echelon and associated with the supporting members, a horizontal arm mounted to swing into position to receive a single match from the adjacent sliding member, a rotatable 90 shaft having a spiral groove and supporting said arm and a lug carried by one of the sliding members and engageable with the spiral groove formed in the rotatable shaft, whereby, a movement of the feeding means 95 will swing the said arm.

3. A mono delivery match safe comprising a casing having a discharge opening and a hopper, means for feeding the matches to the discharge opening, said means including 100 match supporting members arranged in echelon and associated with sliding members, a grooved horizontally swinging arm for delivering a single match from the feeding means and means independent of said 105 arm for preventing the accidental displacement of the match.

In testimony whereof I affix my signature in presence of two witnesses.

GEORGE JACOB DEINES.
